BOTTLE CLOSURE

José Luis Conde, Buenos Aires, Argentina

Application October 29, 1934, Serial No. 750,562

5 Claims. (Cl. 215—22)

The present invention is a continuation in part of my copending application Serial No. 698,528 filed November 17, 1933, for "Bottle stoppers", filed in the name of José Luis Conde Perez, Perez being my maternal surname, which I have dropped in filing this application, and the invention refers to an automatic closure device, for preventing the refilling of bottles, vessels and the like, as also to the system for anchoring same in the interior 10 of the neck of the bottle.

On designing same, care has been taken that same be as simple as possible, having into account that means be provided for obtaining a convenient exit of the liquid when pouring, independently of the entrance of air, for the purpose that such exit of liquid be continuous.

The seat of the valve with which is provided the closure device, is divided by means of a central partition, so that there exist in the said 20 seat two passages, one for the liquid and the other for the air, both being closed or opened at the same time by means of the same valve.

As a modified form of construction, the closure device may be provided with two valves, one 25 of them being a floating valve for preventing any possibility of refilling the bottle when this is placed in the up-side-down position.

The closure device is fixed in the interior of the neck of the bottle, by means of two or more 30 small plates of elastic material, such as cork or rubber, which are adhered to the lateral surface of the closure device and at the same time to the internal surface of the bottle neck. These small plates may serve as labels, printing or otherwise applying on them the trade-mark of the product or any other sign that will be seen from the exterior, through the neck of the bottle.

Moreover, for making the anchoring of the closure device more effective and for preventing the 40 insertion of a wire or similar device between the closure device and the internal surface of the neck of the bottle, same is provided with two bands of elastic material, cork or rubber, that encircle the closure device, leaving between same, at each 45 side, respective free spaces that serve as passages for the exit of the liquid.

These two bands are placed in such a form that the free spaces mentioned occupy a position perpendicular to the openings of the closure device 50 that correspond to the exit of the liquid and to the entrance of the air.

These elements, plates forming the guarantee labels and bands that the closure device carries, are adhered to the internal surface of the bottle 55 neck and if an attempt is made to withdraw

the closure device from its place, that said plates and bands will become spoiled and being then visible from the exterior of the bottle, the violation would be put in evidence.

With the object that the invention be clearly understood and easily carried into practice, same has been shown on its preferred form of construction in the drawings that accompany this specification.

In the drawings:

Fig. 1 is a lengthwise cut view of the closure device applied to the neck of a bottle,

Fig. 2 is an exterior view of same, seen from the side corresponding to the passages of the liquid,

Fig. 3 is a lengthwise cut view according to 15 plane *a*—*b* of Fig. 2,

Fig. 4 is a view of the top part of the closure device,

Fig. 5 shows a cross cut view according to plane 20 *c*—*d* of Fig. 3,

Fig. 6 shows a cross cut view according to plane 25 *e*—*f* of Fig. 3,

Fig. 7 is a view similar to the former, without showing the valve, so that the seat of same can be seen,

Fig. 8 shows the form how the closure device works, when exit of the liquid takes place,

Fig. 9 shows the form how the closure device works when same is carried to the horizontal position,

Fig. 10 is an exterior view of the closure device seen from the side corresponding to the guarantee labels, which are constituted, as it has been said, by the fixing plates,

Fig. 11 shows a view similar to the former, the 35 closure device having been moved from its position, a fact that is put into evidence by the spoiling appearance that present the labels and the band or ring,

Fig. 12 shows a lengthwise cut view similar to 40 that of Fig. 3, illustrating a closure device provided with double valve, one of them being a floating valve, and

Fig. 13 shows how these elements work when it is intended to refill the bottle, being thus placed 45 in the up-side-down position,

In the drawings, the same signs of reference designate similar or equivalent parts.

The automatic closure device, formed of a single part, is constituted by two principal parts; one 50 serving as a defence is provided with the ducts for the exit of the liquid and the entrance of the air and the other constituted by the seat of the valve and the corresponding valve.

It has been indicated as 1, the body that carries 55

the ducts 2 for the exit of the liquid and 3 for the entrance of the air, adopting these ducts the form shown, i. e. zig-zag with acute angles, with the object that from the exterior of the bottle, 5 it will be impossible, with the aid of a wire or the like, to spoil the valve. The said body forms a single part with the seat of the valve 4, being united by means of partial walls 5, that provide in the centre of the closure device, an empty 10 space 6.

The seat 4 of the valve is divided, transversally, by means of a central partition 7 so that two passages are provided, one 8 placed in the direction of the duct 2 and another 9, placed in the direction of the duct 3, the bottom one of which, for 15 any position of the bottle, serves for the exit of the liquid, while the top one serves for the entrance of the air. Both passages are covered with a single valve 10, which, in the normal vertical position of the bottle, the said valve is pressed by a counterweight 11, that is placed in space 6, the said counterweight adopting the form similar to that of a cut inverted pyramid, as 20 it is clearly seen in the drawings.

25 This counterweight 11, is provided laterally with hollows 12 and 13 for facilitating, respectively, the exit of the liquid and the entrance of the air.

The working of the said elements may be 30 readily understood by referring to the illustrating drawings. As it can be seen in Fig. 8, it is sufficient to incline the bottle and under these conditions counterweight 11 will fall, as also the valve 10, permitting the free exit of the liquid that 35 follows the arrows *m*, flowing through passage 8, hollow 12, duct 2 that are placed in the same direction, flowing after to the exterior. At the same time, the air enters following the arrows *n*, flowing through duct 3, hollow 13 and passage 40 9, arriving to the interior of the bottle.

The valve only opens when the bottle is turned and in the horizontal position of same and even before reaching that position, the valve 10 closes, as indicated in Figure 10, by the action of the 45 counterweight 11, that rests on the valve. This prevents the refilling in this position.

For the system of anchoring, the closure device has been provided with two lateral hollows 15 where it is adhered a thin plate 16 of an elastic 50 material such as cork or rubber, that also constitutes a guarantee label, being, for the purpose, printed or otherwise marked with a trade-mark or any other sign 17 (Fig. 10) that can be seen from the exterior of the bottle or vessel. This 55 label or thin plate is covered by a thin coat 18 of any adhesive fixing product that solders same strongly to the internal face of the neck 14 of the bottle, so that the closure device 1, by means of these labels 16, is made a whole with the neck 60 14 of the bottle.

Moreover, towards the top part of the closure device 1, provision is made of two thin plates 19 of any elastic material, that partially encircle the closure device, leaving between the ends of both, a free passage 20, as it can be seen in Figures 4, 9, and 10. These bands 19 may be placed, as in the case of label shown in Figure 10, covered with a coat of a fixing product that will adhere 65 same to the internal surface of the neck of the bottle, carrying also, if necessary, any sign or the name of the product as indicated with 21 in Figures 2 and 10.

Besides that these two bands 19 reinforce the 70 anchoring of the closure device, they serve also,

as it has already been said, for difficulting the introduction of a wire or the like between the wall of the closure device 1 and the internal surface of the neck, that would make possible to difficult the working of the valve. As it will be understood, these bands 19 constitute a defence for 75 these purposes, since if a wire is introduced through the free spaces 20, the wire will meet label 16.

If it is intended to withdraw closure device 1, 10 as soon as this has been slightly moved, is produced a displacement of the label 16 and as same is adhered to the neck, label 16 will be spoiled, and will present the appearance indicated in Figure 11.

15 This fact will also be denunciated by sign or mark 21 of bands 19 if they have been adhered to the neck of the bottle, as in the former case.

The free spaces 20 provided between the ends 20 of the bands 19, serve as a help to the pouring, since they facilitate the exit of the liquid and the entrance of the air.

In the top part of the neck of the bottle, a free 25 space 22 may be provided, for permitting the insertion of a usual cork.

In the modified form of construction shown in Figures 12 and 13, addition has been made of a valve or floating element 23, of cork or the like. In the normal vertical position of the bottle, this 30 valve, has no influence, but on the contrary, it has effect when it is intended to refill the bottle in the up-side-down position as shown in Figure 13. If a slow current of liquid is initiated towards the interior of the bottle, as it is indicated with the arrows *p*, for little by little making compression of the air in the bottle, the floating valve will be raised carrying the valve 10 to apply 35 against the seat 3, for preventing the entrance of the liquid.

It is evident that many modifications may be 40 introduced in the construction and details, without departing from the scope of the invention which is more clearly set forth in the claims that follow the present specification.

Having now particularly determined and ascertained the nature of my invention and how same 45 can be carried into practice, I declare that what I claim, is:

1. A closure device for non-refillable bottles, comprising a body dimensioned to fit in the neck of the bottle and having two independent ducts extending longitudinally therethrough, for the passage of air and the liquid, a valve seat consisting of part of said body and formed across the bottom of the latter and having a transverse partition thereacross defining two separate passages for the passage of air and the liquid, said body having a centrally disposed hollow in its lower part, above said valve seat, a single plate valve disposed loosely in said hollow above said seat, a counterweight in said hollow above said valve, having substantially the shape of a cut inverted pyramid, and having guiding recesses therein cooperating with the first-mentioned recesses, for the exit of the liquid and the entrance of the air, said valve, under the influence of said counterweight, normally covering the interior of said bottle to said ducts, the said counterweight forcing said valve home on its seat before the bottle is restored from a pouring into a horizontal position, the valve and counterweight uncovering the interior of the bottle to both sets of ducts when the bottle is moved to its pouring position, and means for anchoring said closure device in the neck of the bottle.

2. A closure device for non-refillable bottles, comprising a body dimensioned to fit in the neck of the bottle and having two independent ducts extending longitudinally therethrough, for the passage of air and the liquid, a valve seat consisting of part of said body and formed across the bottom of the latter and having a transverse partition thereacross defining two separate passages for the passage of air and the liquid, said body having a centrally disposed hollow in its lower part, above said valve seat, a single plate valve disposed loosely in said hollow above said seat, a counterweight in said hollow above said valve, said valve and said counterweight normally covering the interior of said bottle to said ducts, but uncovering them when the bottle is moved to its pouring position, means for anchoring said closure device in the neck of the bottle, and at least two devices of elastic material adhered to both the exterior lateral face of the closure device and to the interior of the neck of the bottle and carrying frangible indicia thereon, the said indicia being clearly readable from the exterior when the indicia-carrying devices are in proper position, and being capable of being distorted and destroyed when said devices have been moved and the seal with the neck of the bottle broken in an attempt to remove the closure device.
- 5 10 15 20 25 30 35 40 45 50 55
3. A closure device for non-refillable bottles, comprising a body dimensioned to fit in the neck of the bottle and having two independent ducts extending longitudinally therethrough, for the passage of air and the liquid, a valve seat formed across the bottom of said body and having a transverse partition thereacross defining two separate passages for the passage of air and the liquid, said body having a centrally disposed hollow in its lower part, above said valve seat, a single plate valve disposed loosely in said hollow above said seat, a counterweight in said hollow above said valve, said valve and said counterweight normally covering the interior of said bottle to said ducts, but uncovering them when the bottle is moved to its pouring position, means for anchoring said closure device in the neck of the bottle, and a device adhered to both the lateral surface of the closure device and the interior surface of the neck of the bottle, and carrying frangible indicia thereon, the said indicia being clearly readable from the exterior when the indicia-carrying device is in proper position, and being capable of being distorted and destroyed when said device has been moved and the seal to the bottle neck broken in an attempt to remove the closure device.
- 30 35 40 45 50 55
4. A closure device for non-refillable bottles, comprising a body dimensioned to fit in the neck of the bottle and having two independent ducts extending longitudinally therethrough, for the
- passage of air and the liquid, valve seat formed across the bottom of said body and having a transverse partition thereacross defining two separate passages for the passage of air and the liquid, said body having a centrally disposed hollow in its lower part, above said valve seat, a single plate valve disposed loosely in said hollow above said seat, a counterweight in said hollow above said valve, said valve and said counterweight normally covering the interior of said bottle to said ducts, but uncovering them when the bottle is moved to its pouring position, means for anchoring said closure device in the neck of the bottle, and at least two devices of elastic material adhered to both the exterior lateral face of the closure device and to the interior of the neck of the bottle and carrying frangible indicia thereon, the said indicia being clearly readable from the exterior when the indicia-carrying devices are in proper position, and being capable of being distorted and destroyed when said devices have been moved and the seal with the neck of the bottle broken in an attempt to remove the closure device.
- 5 10 15 20 25 30 35 40 45 50 55
